UNITED STATES PATENT OFFICE.

CLARENCE W. UTZMAN, OF CHICAGO, ILLINOIS.

BUILDING-CONSTRUCTION ELEMENT.

1,203,283.

Specification of Letters Patent.

Patented Oct. 31, 1916.

Application filed August 30, 1915. Serial No. 47,967.

To all whom it may concern:

Be it known that I, CLARENCE W. UTZMAN, a citizen of the United States, residing at Chicago, in the county of Cook and State of Illinois, have invented certain new and useful Improvements in Building-Construction Elements, of which the following is a specification.

This invention relates in general to building constructions, and is designed to comply with modern fire-proof requirements and to supply a fire-proof element for use in constructions in place of wood or other combustible material.

15 In modern buildings which are constructed with a view to making them as nearly fire-proof as possible, it is customary to employ a skeleton steel construction surrounded by tile, concrete, or other fire-resisting material.

20 and to make the floors of concrete or other fire-proof construction. Wooden floors are, however, customarily laid over the concrete, and in order to fasten the floors down wooden screeds are embedded in the concrete to which the floor boards are nailed.

25 The vertical partitions also, particularly the inside partitions, are usually formed by using wooden uprights to which either wood or metal lath are nailed and then covered

30 with plaster. In order to make the partitions somewhat fire-resistant, slabs or sheets of plaster board are frequently used instead of metal or wooden lath, but a fire of considerable magnitude will soon heat through

35 the wall structure and set fire to the wooden uprights of the partition. It has long been recognized therefore that the wooden uprights in the partitions are a very weak portion of the building from a fire-proof stand-

40 point. The wooden screeds beneath the floor are also unsatisfactory because they rot and disintegrate with great rapidity.

One of the primary objects of my present invention therefore is to provide a building

45 construction element of fire-proof construction which can be formed in various shapes, to be used as uprights in partitions, screeds beneath the floors or as beams, girders or joists, anywhere in the building where wooden members have heretofore been used.

50 Another object is to provide an element of the character above mentioned which will

not only be fire-proof but will be so constructed that nails, screws or other fastening devices may be driven into it practically 55 as they have heretofore been driven into wood. My improved element may therefore be embodied in the concrete floors and used as screeds to which the wooden flooring may be nailed or screwed, and they may be used 60 as uprights for inside partitions to which plaster board or metal lath or other covering may be nailed, stapled or otherwise fastened, thereby providing a construction which will be entirely fire-proof.

65 A further object of my invention is to provide a building construction element which can be sawed to any desired length the same as wooden elements have been previously sawed, to fit anywhere desired.

70 Other objects and many of the attendant advantages of my invention will be readily appreciated as the same becomes better understood by reference to the following description, when considered in connection 75 with the accompanying drawings.

Referring to the drawings—Figure 1 is a fragmentary perspective view of an element embodying my invention, a portion of the plastic material being removed to more 80 clearly show the interior construction; Fig. 2 is a similar view of a modified form of reinforcing member; Fig. 3 is a view similar to Fig. 1, showing a member formed to provide a screed; Fig. 4 is a fragmentary sectional view of a building construction showing the use of a screed such as is shown in Fig. 3, and Fig. 5 is a fragmentary view of a building construction showing the use of an element such as is disclosed in Fig. 1. 90

95 On the drawings reference character 6 indicates generally a building construction element in the form of a beam or joist which comprises a body 7 of plastic material, preferably stucco, or calcined gypsum, or concrete which is molded to the required dimensions substantially similar to the dimensions of a wooden girder, which it is designed to supplant. The body of plastic material possesses extremely high fire-resisting qualities, 100 but since this material of itself does not possess the requisite tensile, compression and shearing strength, and has little capability of retaining nails, screws or other fastening

devices, I have provided a reinforcement therefor which also acts as a fastening device retainer, the construction of which will now be described.

5 Referring more particularly to Fig. 1, it will be observed that this reinforcing element comprises primarily a metal sheet 8 sufficiently light to permit nails or screws to be inserted therethrough, the intermediate portion of the sheet being disposed along the longitudinal axis of the plastic body and extending vertically or, in other words, in the direction of the greatest transverse dimension of the element. The upper and 10 lower edges of the reinforcing member are bent to produce a plurality of transversely extending folds 9, each ply of the folds being separated from the next adjacent ply a sufficient distance to permit the space between the plies to be filled by the surrounding plastic material. These folds not only 15 strengthen the element but also provide an area slightly narrower than the width of the element, into which nails, screws, or other 20 fastening devices, may be driven or threaded. 25 When a nail or screw, for instance, is driven into the edge of the element and through a plurality of plies of the fold the metal of each ply is bent inwardly as the nail passes 30 therethrough and when the nail has been driven home it is embraced by the surrounding metal in a plurality of places so as to be firmly retained in position against withdrawal, as it would be when driven into a 35 wooden element.

In order to form a more effectual bond for the body of plastic material I prefer to provide an intermediate portion of the reinforcing element between the longitudinal folds 40 at each edge with a plurality of openings 45 11 which are formed by striking up or bending laterally a portion of the metal as shown in Fig. 1. When the element is molded the plastic material will flow through the openings and form a rigid permanent bond.

For the purpose of further strengthening the element I employ a plurality of reinforcing devices or chairs, designated generally by reference character 12. Each chair 50 is formed of metal which is preferably substantially channel-shaped, the side flanges 13 being cut out or provided with recesses 14 arranged to receive the sides of the folds 9 and to provide teeth or lugs projecting between the folds so that the folds at the top 55 and bottom of the element are firmly engaged by the chairs. The metal of the body or central portion of each chair is preferably cut and bent inwardly to provide an opening 60 15 through which the plastic material flows when the element is formed, thereby firmly bonding and locking the chair to the reinforcing member and into the structure of the element. These chairs may be cheaply

formed of metal steel stampings, or they 65 may be stamped from solid bars.

In Fig. 2 I have shown a slightly modified form of reinforcing member, in which the web or central portion 16 instead of being provided with openings 11 of the form shown in Fig. 1 has portions of the metal struck up laterally from the body thereof to provide anchors 20 projecting from each face of the web to which the plastic material of the element is anchored. The folds 17 70 are similar to the folds 9, shown in Fig. 1, and I contemplate the employment of chairs 12 in connection with this form of reinforcing member as well as with that shown in Fig. 1. It should be understood that the 75 chairs 12 are arranged in spaced relation throughout the length of the element, as many chairs being used as may be deemed desirable, depending upon the purpose for which the element is to be used, the chairs 80 serving as struts to transmit the load from chord to chord, and also keeping the beam in equilibrium, and it should also be understood that the height of the web or intermediate portion 8 of the reinforcing member, and the length of the chairs 12, may be 85 varied, depending upon the depth of the particular element in any particular instance. An element proportioned substantially as shown in Fig. 1 is designed to be used as a 90 beam or girder. A smaller and shallower construction would be best adapted for use as uprights in interior partitions. The 95 described construction also readily permits variations in the weight bearing strength of the element by changing the chord section,—that is, increasing or decreasing the number of folds while not changing the web. The 100 depth and other dimensions of the element will, of course, be regulated to suit the requirements for which the elements are to be used.

In Fig. 3 I have illustrated an embodiment of my invention which is designed to be used as a screed, and referring to this 110 figure, it will be apparent that the reinforcing member 18 is much shallower than that shown in Figs. 1 and 2, the intermediate web portion being entirely omitted so that the element consists merely of a plurality of 115 folds of the metal. Chairs 19, shaped for insertion between the various folds and adapted to engage therewith, are employed to strengthen and lend rigidity to the construction. The metal parts are embedded in 120 a body of suitable plastic material 21, as will be readily understood.

In Fig. 4 I have illustrated a screed, which is designated by reference character 22, laid in position in a concrete or other poured 125 floor construction 23, the details of construction of which are immaterial so far as my present invention is concerned. The rough

floor 24 is securely fastened to the screed by nails or screws 25 driven through the floor and into the screed, the screed, of course, being laid with the plies of the fold 5 in horizontal position. The finishing floor 30 is laid over the rough floor in the usual manner.

In Fig. 5 I have illustrated a fragment of the floor construction embodying that form 10 of my invention illustrated in Fig. 1. In this instance the beam 6 is supported at each end, preferably upon the I-beams of the building frame, and a layer of plaster board 26 is laid over the beam and secured thereto by nails or screws 27. The concrete or stucco 28 is then poured over the plaster board and a floor surface of suitable construction is then imposed upon the concrete. The ceiling 15 of the floor beneath may be attached to the beam 6 in any preferred manner, but I have illustrated a layer of plaster board 29 secured by nails or screws 31, the joints being sustained by clips 32 and the plaster 33 being applied to the under-surface of the 20 plaster board.

Where extra tensional strength in the tension region of the element is desired, this may be readily obtained by means of wires or bars (not shown) laid between the folds 30 on the tension side of the member.

It should be apparent from the foregoing that I have provided a building construction element which is capable of use as a substitute for wooden beams, girders, joists, 35 uprights or screeds, and that while my construction is entirely fire-proof it affords provision for nailing or screwing lath, plaster board or other constructions thereto. The metal reinforcing members are made sufficiently thin and soft to permit driving of 40 nails into them, and the elements may be sawed to the required length by means of ordinary hand saws.

While I have shown but two types of elements embodying my invention it should be manifest that they may be made in various sizes and lengths suitable for various purposes, and that the contour or outside shape 45 and appearance of the plastic body may be varied as desired by simply employing a mold of the requisite shape.

I claim:

1. A building construction element comprising an elongated body of plastic material having embedded therein a plurality 50 of parallel longitudinally extending strips of metal spaced apart and adapted to retain fastening devices inserted therethrough, and means engaging the edges of said strips and 55 extending transversely of the element for strengthening and reinforcing the element, the spaces between said strips and around said reinforcing means being filled with said plastic material.

2. A building construction element, comprising a reinforcing member providing relatively deep and narrow superposed folds extending in parallel relation crosswise of the element the plies of said folds being spaced apart so as to be adapted to receive 65 and retain nails or similar fastening devices inserted therein, said member being embedded in a form body of hardened plastic material which fills the spaces between the plies of said folds. 75

3. A building construction element comprising a body of plastic material surrounding a metal sheet formed adjacent the top and bottom of the element so as to provide a plurality of spaced transverse plies separated from each other by said plastic material and adapted to receive and retain nails or similar fastening devices, said metal sheet having an intermediate web extending along the longitudinal axis of said element 80 between the upper and lower transverse plies. 85

4. A building construction element comprising a body of plastic material shaped to form a beam or the like having embedded 90 therein a metal sheet comprising a central portion perforated to permit bonding of the surrounding plastic material, and a portion formed by bending the metal to provide a plurality of relatively deep and narrow sub- 95 substantially parallel transversely extending folds spaced apart by said plastic material and adapted to receive and retain a fastening device inserted therein.

5. A building construction element, comprising a beam or the like of plastic material having embedded therein a sheet metal member folded along one longitudinal edge to provide a series of spaced plies arranged substantially parallel with the adjacent face 100 of the beam and extending across the beam nearly to the opposite sides thereof in position to receive and retain fastening devices inserted therethrough the space between adjacent plies being filled with said plastic 105 material. 110

6. A building construction element, comprising a sheet metal member shaped to provide transversely disposed relatively deep and narrow folds, means engaging the edges 115 of said folds to strengthen and retain the same in position, and a body of plastic material surrounding said member and said means.

7. A building construction element, comprising a body of plastic material shaped to form a beam or the like having embedded 120 therein a metal sheet provided at the top and bottom with a plurality of transversely extending folds between which said plastic 125 material is disposed, intermediate portions of said metal being bent laterally from the main body to provide anchorage for the

plastic material, and metal chairs embedded in said plastic material and engaged with said folds to strengthen and reinforce the element.

5. 8. A reinforcing member for a plastic building construction element, comprising a sheet of metal bent to provide a plurality of

relatively deep and narrow transversely extending folds superposed along the longitudinal edges of said member the plies of 10 said folds being of substantially equal width transversely of the element and spaced apart throughout their length.
